EDWARD R. TISCHER, OF HOUSTON, TEXAS, ASSIGNOR OF FORTY PER CENT TO GUS EMMERT, OF HARRIS COUNTY, TEXAS.

COTTON GIN.

1,418,106.

Specification of Letters Patent. Patented May 30, 1922.

Application filed March 16, 1920. Serial No. 366,251.

To all whom it may concern:

Be it known that I, EDWARD R. TISCHER, citizen of the United States, residing at Houston, in the county of Harris and State 5 of Texas, have invented certain new and useful Improvements in Cotton Gins, of which the following is a specification.

This invention relates to new and useful improvements in a cotton gin.

10 One object of the invention is to provide a gin of the character described whereby the lint cotton may be stripped from the seed and the lint and seed separated from each other.

15 Another object of the invention is to provide a device of the character described whereby the lint cotton, after it is separated from the seed, will be freed of all mats, or compact masses, and will be reduced to a 20 loose and fluffy state.

A further feature of the invention is to provide the combination with a ginning roller, of a stripper roller and a stripping shoe which cooperate to strip the lint from 25 the seed, said stripper roller and shoe being so arranged that they may be readily withdrawn from the ginning roller for repairs or inspection.

30 A further feature resides in the combination with a spiked roller of a brush by the co-operation of which the lint cotton after being freed of the seed will be separated into a uniform loose and fluffy mass.

35 A still further feature consists of conveyors, operated in a novel manner for conveying away dirt or other waste materials.

With the above and other objects in view the invention has particular relation to certain novel features of construction, operation 40 and arrangement of parts, an example of which is given in this specification and illustrated in the accompanying drawings, wherein:—

Figure 1 shows a front view with certain 45 parts removed for the sake of clearness,

Figure 2 shows a vertical sectional view.

Figure 3 shows the gearing employed,

Figure 4 shows an enlarged edge view of the stripper shoe, and

50 Figure 5 shows an enlarged fragmentary view of the conveyor driving mechanism.

Referring now more particularly to the drawings, wherein like numerals of reference designate similar parts in each of the 55 figures, the numeral 1 designates the end

members, or legs of the casing which are supported on any suitable base as 2. Rotatably mounted in suitable bearings in the upper part of these end members is the transverse shaft 3, and fixed upon this shaft, within the 60 casing, is the ginning roller 4. This roller 4 is partially surrounded on the rear by the arcuate hood 5 which forms the upper part of the back of the casing and this hood has a long transverse slit 5' therein for the intake 65 of air. In front of the ginning roller, and slightly above it there is the stripper roller which is fixed upon the transverse shaft 6 and surrounded by the arcuate hood 7. The shaft 6 is rotatably mounted in suitable bearings carried by the ends 8, 8 of the hood 7. The stripper roller is formed of end spiders 9 to which the ends of the stripper bars 10 are secured. These bars are spaced apart and have radiating holes or bearings through 75 which the stripper fingers 11 loosely fit. The inner ends of these fingers are formed with heads which prevent them from being thrown outwardly by centrifugal force and these heads may contact against the shaft 6, 80 when this roller is at rest, to prevent them from dropping out. Above the ginning and stripper rollers there is a transverse hopper 12 into which the seed cotton is delivered from the feeder (not shown). The upper 85 edge of the hood 5 is secured to the back side of this hopper, and the upper edge of the hood 7 rests against the front side thereof while the gin is at work. The lower edge of the hood 7 is fastened to the inner edge 90 of the forwardly declining transverse blade bar 13, which is arranged in front of the gin. The outer edge of this blade bar has bearings on a transverse rod 14, which is fixed in suitable bearings carried by the end 95 members 1, 1 and a hand lever 15 is secured to this blade bar. A transverse stripper blade 16 is fastened at its lower edge to the inner edge of the blade bar and the free edge of this blade is arranged tangentially with 100 respect to the front side of the ginning roller, as shown in Figure 2. This blade is preferably formed of a plate of bronze backed by a steel plate which is riveted thereto so that when the ginning roller and the blade 105 become heated by friction with the cotton, the bronze plate will expand more than its steel backing and operate to carry the free edge of the blade, and the stripper shoe 17, carried by said edge, away from the ginning 110

roller to compensate for the expansion of said ginning roller and maintain their relative adjustment. The stripper shoe 17 is also composed of bronze and is formed of sections as shown in Figure 4. Each section is formed of a plate doubled together thus forming a two ply shoe and the upper side of each section has the outwardly turned keepers 18, 18 which engage over the free edge of the blade 16 to hold the shoe in frictional relation with the front side of the ginning roller. In order to gain access to the stripper roller and stripping shoe 17, for inspection, or repairs, or for other purposes, the lever 15 may be pulled forwardly which will operate to withdraw said members, together with the blade bar and blade, from the ginning roller, as illustrated in dotted lines in Figure 2. Upstanding from the base 2 and spaced apart are the bearings 19, 19 wherein the shaft 20 is rotatably mounted. Each end of this shaft has an arm 21 fixed thereon and the shaft also has a foot lever 22 fixed thereto. Hooks 23, 23 are pivoted at their lower ends to the free ends of the respective arms 21, 21 and their upper ends are formed to engage over the depending catches 24, 24 carried by the underside of the blade bar 13. Adjacent the foot pedal there is the standard 25 which is secured to, and stands up from the base 2 and the upper end of this standard is overturned and has the adjusting bolt 26 threaded therethrough. The lower end of this bolt is connected to a bearing block 27, which is vertically adjustable on said standard and through this bolt the block may be adjusted up and down. When the pedal 22 is engaged under the block 27 said pedal is locked against upward movement and operates, through the hooks 23, to lock the blade bar 13, and its appendants, above described in position for ginning. By a lateral movement the pedal may be released and then moved upwardly to release the hooks from the catches 24. When said hooks are moved upwardly the inclined shoulders 23' thereof moving against the release blocks 28 operate to disengage the hooks from their respective catches thus unlocking the blade bar and permitting the manipulation of the hand lever 15 for the purpose above explained.

Underneath the ginning roller there is a drum-like fan 29, which is fixed upon the transverse shaft 30, rotatable in suitable bearings in the end members 1, 1. This fan is partially surrounded in front by means of an arcuately formed casing front 31, which is preferably formed of sheet metal, and continues upwardly, surrounding the lower part of the ginning roller in front. The upper edge of this casing front is spaced from the inner edge of the blade bar to provide an air inlet 32. Above this fan, and arranged 65 to co-operate therewith there is the spiked

roller 33, consisting of a drum and projecting spikes which radiate therefrom. This roller is mounted on the shaft 34 which rotates in suitable bearings carried by the end members 1, 1. A long chamber, for the reception of dirt and the like, is located behind the roller 33 and is formed with the top and bottom boards 35 and 36, which are spaced apart, and the hinged door 37, forming a closure for said chamber and permitting access thereto.

Within the chamber thus formed there is an arcuately formed screen 38 formed of foraminated material and surrounding the drum 33 behind, said screen forming, in effect, a continuation of the hood 5, which, together form the back of the gin casing. A long brush 39 is fastened to the under side of the top board 35 and its bristles project through the upper part of the screen 38 and cooperate with the spiked roller 33 as hereinafter explained. Fixed upon one end of the shaft 3 there is a drive pulley 40, and a spur gear 41 inside the pulley. A drive belt (not shown) operates over this pulley and rotates the shaft, and ginning roller thereon, in the direction indicated by the arrow in Figure 2. Fixed on one end of the shaft 6 and normally in mesh with the spur gear 41 there is the smaller spur gear 42, through which rotation is imparted from the gear 41 to the stripper roller. An idler gear 43 is loosely mounted on one end of the rod 14 and is in mesh with the gear 6 and this gear 43 carries the pulley 44 through which the feeder (not shown) is driven.

The other end of the shaft 3 carries a fixed pulley 45 in alignment with a smaller pulley 46 which is fixed on the end of shaft 3 and a belt 47 operates over these pulleys and transmits rotation from the former to the latter and thus driving the fan 29. The inner end of the pulley 45 is extended and formed into a grooved pulley 48, aligned with a corresponding grooved pulley 49 fixed on the shaft 34, and operating over these last named pulleys there is the cross belt 50 which transmits rotation from the former to the latter and to the spiked roller 33.

In front and rear of the gin there are the respective belt conveyors 51 and 52 which are driven by the rollers 53 and 54, respectively, which are fixed on the front and rear ends, respectively, of the shaft 55. Loosely mounted on the forward end of the shaft 55 there is an elongated hood 56 and pivoted to this hood there is a ratchet-lever 57 whose inner end is formed with ratchet teeth 58 provided to engage and release the shaft 55, as hereinafter explained. The corresponding end of the shaft 34 has an arm 59 fixed thereon and a link 60 is pivoted at its respective ends to the free ends of said arm and ratchet lever. As the shaft 34 rotates it op-

erates through the arm 59 and the link 60 to oscillate the lever 57 and to alternatively engage the teeth 58 with, and release them from, the shaft 55 and to thereby impart successive partial rotations to said shaft, and, through it, to move said conveyors intermittently. These conveyors carry away the seed dirt and other refuse discharged from the stripper roller, and the feeder.

10 The cotton to be ginned is delivered by the feeder into the hopper 12 and the ginning roller carries said cotton into contact with the stripper shoe 17. This shoe arrests the seed but the lint cotton is carried on, by 15 friction of the ginning roller 4, between said roller and shoe. As before stated, this shoe sets on the upper edge of the blade 16 and has more or less freedom to rock back and forth thereon so as not to bind too 20 closely against the ginning roller and thus to permit the lint to pass but to arrest the seed. The stripper fingers beat against the seed cotton, held by said shoe, and loosen up the fiber and remove the seed and dirt therefrom which are discharged through the openings 61 cut through the front side of the 25 hood 7 and fall on to the belt 51. The rotation of the fan 29 creates a suction through the air inlets 5' and 32 and the lint cotton 30 is carried by the air current on down through the casing into contact with the spiked roller 33. The spikes 62 of this roller, project out far enough to prevent any of the lint from passing down in front of said roller, and 35 they engage with said lint and sweep the same around the screen 38 and into contact with the long brush 39 which operates to further separate and loosen the fiber and any remaining dirt and refuse therein is released 40 and blown through said screen and falls into the chamber 63 from which it may be removed through the door 37. The lint cotton 45 is then caught up by the fan 29 and carried around in front of it and discharged through the outlet 64. When the stripping roller and 50 blade are withdrawn, as shown in dotted lines in Figure 2, the spur gear 42 will ride around the gear 43 into the position shown in dotted lines in Figure 3, and will thus be carried out of mesh with the spur gear 41. The stripping roller will thus be stopped for the inspection and repair of it or the stripper shoe, and the feeder will also be stopped to prevent the delivery of cotton to the gin.

55 What I claim is:—

1. A cotton gin including a casing, a ginning roller rotatably mounted therein, a stripping roller arranged to cooperate with the ginning roller, loosely mounted fingers carried by the stripping roller, a shoe arranged in tangential relation to the ginning roller and provided to arrest seed cotton carried into contact with it by the ginning roller to permit the fingers of the stripping roller

to operate against said cotton to strip the seed from the lint thereof.

2. A cotton gin including a casing, a ginning roller rotatably mounted therein, a shoe arranged in tangential relation to the ginning roller and provided to arrest the seed cotton carried into contact with it, by said roller, a stripping roller rotatably mounted in the casing and provided with loosely mounted fingers which beat against said cotton held by said shoe to remove the seed therefrom said ginning roller meanwhile operating to carry the feed lint, by friction between said ginning roller and shoe.

3. A cotton gin including a casing, a ginning roller rotatably mounted therein, a stripping roller arranged to cooperate with the ginning roller, a stripper blade arranged in tangential relation to the ginning roller, a removable shoe mounted on the blade and provided to arrest seed cotton carried into contact with it by the ginning roller, to permit the stripping roller to operate against said cotton to strip the seed from the lint thereof, and means for withdrawing said stripping roller and shoe out of operative relation with the ginning roller.

4. A cotton gin including a casing, a ginning roller rotatably mounted therein, the front part of the casing being formed into a surrounding hood which is hinged with respect to the gin, a stripping roller rotatably mounted in said hood, a stripper blade secured to the hood and arranged tangentially with respect to the ginning roller and located between said rollers a shoe fitted over the free edge of the blade means for holding said stripping roller and shoe out of, or in operative relation with the ginning roller, and means for locking them in the last mentioned relation.

5. A cotton gin including a casing, a ginning roller rotatably mounted therein, a means arranged to cooperate with said roller whereby the cotton seed are arrested while the lint is stripped therefrom by said roller, a suction fan arranged in the casing underneath the roller and provided to create an air current through the casing whereby the lint is drawn from said roller, a spiked roller rotatably mounted in the casing above the fan, and rotatable in an opposite direction from the fan rotation, a screen surrounding said spiked roller in the rear and a fixed brush arranged to cooperate with said spiked roller.

6. A cotton gin including a casing, a ginning roller rotatably mounted therein, the front part of the casing being formed into a surrounding hood, provided with openings, a stripping roller rotatably mounted in said hood, a shoe cooperating with the ginning roller and arranged to arrest the seed cotton carried into contact therewith by

- the ginning roller, fingers carried by the stripping roller which beat against the cotton held by said shoe to remove the seed and foreign matter therefrom which are discharged through said openings, a belt conveyor arranged to receive said seed and foreign matter so discharged through said openings, and means for intermittently moving said conveyor.
- 10 7. In a cotton gin a stripper blade formed of bronze backed by a steel plate which is riveted thereto.
8. In a cotton gin a stripper blade formed of bronze backed by a steel plate which is riveted thereto and a stripper shoe set on the free edge of said blade.
- 15
9. In a cotton gin a ginning roller, a blade arranged in tangential relation thereto and a stripper shoe formed of sections and set on the free edge of the blade. 20
10. In a cotton gin, a stripping roller including a shaft, a drum fixed thereon and formed of lengthwise bars provided with radiating bearings, and stripper fingers loosely mounted in said bearings. 25

In testimony whereof I have signed my name to this specification in the presence of two subscribing witnesses.

EDWARD R. TISCHER.
